(57) **CLAIM**

The ornamental design for a cutting tool, as shown and described.

DESCRIPTION

FIG. 1 is a front view of a cutting tool of a first embodiment showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a cross sectional view taken along line 10-10 in FIG. 1;

FIG. 11 is a cross sectional view taken along line 11-11 in FIG. 1;

FIG. 12 is a cross sectional view taken along line 12-12 in FIG. 1;

FIG. 13 is a cross sectional view taken along line 13-13 in FIG. 1;

FIG. 14 is an enlarged view of the portion 14 in FIG. 12;

FIG. 15 is an enlarged view of the portion 15 in FIG. 13;

FIG. 16 is a view showing the cutting tool in a state of use thereof;

FIG. 17 is a front view of a cutting tool of a second embodiment showing our new design;

FIG. 18 is a rear view thereof;

(Continued)

FIG. 19 is a left side view thereof;
 FIG. 20 is a right side view thereof;
 FIG. 21 is a top view thereof;
 FIG. 22 is a bottom view thereof;
 FIG. 23 is a first perspective view thereof;
 FIG. 24 is a second perspective view thereof;
 FIG. 25 is a third perspective view thereof;
 FIG. 26 is a cross sectional view taken along line 26-26 in FIG. 17;
 FIG. 27 is a cross sectional view taken along line 27-27 in FIG. 17;
 FIG. 28 is a cross sectional view taken along line 28-28 in FIG. 17;
 FIG. 29 is a cross sectional view taken along line 29-29 in FIG. 17;
 FIG. 30 is an enlarged view of the portion 30 in FIG. 28;
 FIG. 31 is an enlarged view of the portion 31 in FIG. 29; and,
 FIG. 32 is a view showing the cutting tool in a state of use thereof.
 The broken lines shown in views represent portions that form no part of the claimed design.
